UNITED STATES PATENT OFFICE.

ELIZA A. COPELAND, OF GARDEN VALLEY, TEXAS.

BALE-TIE.

SPECIFICATION forming part of Letters Patent No. 364,218, dated June 7, 1887.

Application filed January 21, 1887. Serial No. 225,015. (No model.)

To all whom it may concern:

Be it known that I, ELIZA A. COPELAND, a citizen of the United States, residing at Garden Valley, in the county of Smith, State of Texas, have invented certain new and useful Improvements in Bale-Ties, of which the following is a specification, reference being had therein to the accompanying drawings.

This invention has relation to bale-tie buckles; and it has for its object the provision of a tie-buckle that can readily be applied without extraneous fastening devices either with the tie or the buckle itself, and one which can be repeatedly used, and one which can be manufactured at a minimum expense and with the least possible waste of material, and so disposed as to give a maximum of strength.

Other objects and advantages of the invention will appear in the following description, and its novel features will be particularly pointed out in the claims.

Referring to the drawings, Figure 1 is a plan of the buckle connected with the ends of a bale-tie as when applied to use. Fig. 2 is a plan, and Fig. 3 an edge view, of the buckle strengthened as hereinafter described.

A A' represent opposite ends of a bale-tie, each of which is bent to form a loop, as shown, by being bent back upon itself. One of the loops, A', is first connected with the buckle B by being passed through an opening, B', and about an end bar, B², thereof, while the end loop, A, on the opposite end of the tie is passed through a slot, B⁴, into an opposite opening, B⁵, and upon an opposite end bar, B³. This last connection (or both, if desired) is made, as usual, when the bale is under compression, and when released the expansion of the bale causes the tie to be drawn taut, when it is held by the buckle.

My buckle is of rectangular outline with re-entering angles, the upper ends being united by the bar B², and the bar B³ extending from one toward the other of the lower ends, where the slot B⁴ occurs. By adopting this outline I am enabled to save material by cutting the angle B⁶ of one buckle at the time of forming the square corner of another, so that by properly presenting my stock to dies of the form of the buckle much waste is avoided. Furthermore, the same or other dies may be constructed to impinge against the metal along a line—for example, the line B⁷ in the angles B⁶—so as to spread the same outwardly, and thus forming a strengthening fin or web, B⁸. (See Figs. 2 and 3, and dotted lines, Fig. 1.) In like manner all the edges of the buckle may be spread or beveled, in contradistinction to a mere rounding thereof, as shown in Fig. 1, or to a greater extent than that shown, so as to increase the original width and strength of the bars and X-shape bar-uniting portions.

Having described my invention and its operation, what I claim is—

1. The buckle B, having the side re-entering angles B⁶, the bars B² B³, and the slot B⁴, the edges at the apices of the re-entering angles being expanded, substantially as specified.

2. A tie-buckle having re-entering angles B⁶, with strengthening-fins formed therein, substantially as specified.

3. The tie-buckle B, having the angles B⁶, fins B⁸, bars B² B³, slot B⁴, and openings B' B⁵, substantially as specified.

In testimony whereof I affix my signature in presence of two witnesses.

ELIZA A. COPELAND.
